CLAIM

The ornamental design for a keyboard support, substantially as shown and described.

DESCRIPTION

FIG. 1 is a perspective view of a keyboard support illustrating our new design;

FIG. 2 is a front elevation view thereof;

FIG. 3 is a top plan view thereof;

FIG. 4 is a side elevation view thereof, the opposite side being a mirror image;

FIG. 5 is a rear elevation view thereof; and

FIG. 6 is a bottom plan view thereof.

FIG. 1

FIG. 6
